UNITED STATES PATENT OFFICE.

C. MONSON AND S. MOORE, OF NEW HAVEN, CONNECTICUT.

GAS-BURNER.

Specification of Letters Patent No. 31,472, dated February 19, 1861.

To all whom it may concern:

Be it known that we, CHARLES MONSON and STILLMAN MOORE, of the city and county of New Haven, in the State of Connecticut, 5 have invented a new and useful Improvement in Gas-Burners, and do hereby declare that the following is a full and exact description of the construction, character, and operation of the same, reference being 10 had to the accompanying drawings, which make part of this specification, in which—

Figure 1 is a perspective view of the burner complete. Fig. 2 is a section of the same showing how the two parts are connected. Fig. 3 is a perspective view of the 15 same when used with a shade.

Our improvement consists in making the burner of two tubes, one to be passed over the other, in such manner that we can at will 20 easily change or bring the flat, or broadside of the flame to any desired position, or give its fullest light in any desired direction by simply revolving the tip-tube (that is, the tube with the flame to it) turning it by the 25 hand conveniently and without danger of producing leakage.

The drawings show tubes slightly conical. We make the inner tube substantially as indicated at A Fig. 2, suitable to be screwed on 30 to any pipe in the ordinary way. We make the outer tube substantially as shown at B Figs. 1 and 3 and indicated at B B Fig. 2 with a tip as indicated at Figs. 1, 2, 3, or 35 of any suitable shape. And we secure this outer tube in its place by a screw-pin, so as to prevent it being accidentally raised (b Figs. 1, 2, 3) the end of which screw-pin plays in a slight groove around the inner tube, so that the turning tube, slightly lubri- 40 cated, may be freely revolved while the screw-pin prevents it being elevated so as to produce leakage of the burner.

This burner may be used with a shade as indicated in Fig. 3, or without it as indicated in Fig. 1 and with a tip of any kind to give a flat blaze.

The advantages of this improvement consist in that the burner, while the blaze is on, at any time, under any circumstances, may 45 be handily turned with thumb and finger, so as to give the largest amount of light at the

exact point desired and without risk of leakage.

The glass shade in Fig. 3, is meant to be of oval form, the top edges of which come 55 very near to the flat sides of the flame, and it is found by experiment to produce a very steady, non-flickering light. This shade turns with the turning part of the burner.

It is among the advantages of this im- 60 proved burner that a screen, or reflector, may be attached to the turning part, so as to turn with it, and reflect, or screen, the highest degree of the light at different points as may be desired. A screen thus turning with the 65 turning jet must always maintain its relative position to the flame.

As regards the construction of this burner, it is not merely the double tubes which constitute the improvement. We are aware that 70 double tubes have been used, with spaces between and openings for air passages &c. (as in the patent of W. W. Bachelder) which however are not designed for turning at will, but, if turned at all, they require the 75 inconvenient turning of a screw, and give room for leakages every time the burner is turned. And we are also aware that there is a common "fish-tail burner" having what is called a lava tip, a mere bit of porcelain- 80 like composition, tapered a little at one end, and setting in a cone-like cavity where it is designed to be fastened by cement. If it should be merely dropped in, and not cemented, it can be turned when not in use, 85 but while the blaze is on, it is too hot to be touched. We disclaim therefore the two tubes, or tube and cover, for any such purpose as indicated in the Bachelder patent.

What we claim as our invention, and de- 90 sire to secure by Letters Patent, is—

The use of the double tubes, (A, and B,) so as to be readily adjusted in their rotary, without changing their longitudinal position, when constructed, arranged, and fitted, 95 as, and for the purpose, substantially, as herein described.

CHARLES MONSON.
STILLMAN MOORE.
